UNITED STATES PATENT OFFICE.

GEORGE H. GASTON AND CHARLES H. GRANT, OF FOWLERVILLE, MICHIGAN.

WHIFFLETREE.

SPECIFICATION forming part of Letters Patent No. 285,121, dated September 18, 1883.

Application filed June 27, 1883. (No model.)

To all whom it may concern:

Be it known that we, GEORGE H. GASTON and CHARLES H. GRANT, of Fowlerville, in the county of Livingston and State of Michigan, have invented new and useful Improvements in Whiffletrees; and we do hereby declare that the following is a full, clear, and exact description thereof, reference being had to the accompanying drawing, which forms a part of this specification.

This invention relates to certain new and useful improvements in the construction of whiffletrees; and the invention consists in the peculiar construction, arrangement, and combination of the parts, all as more fully herein-after set forth.

In the accompanying drawing, which shows our improved invention in perspective, A represents the double-tree, and B B the single-trees. These are formed from a single rod or bar of iron of the proper size, bent into the elliptic form shown, and with the eyes formed outside the point where the converging ends of the ellipse come in contact with each other, the abutting ends of the rods being welded together between the eye and the truss.

C represents trusses, which are preferably cast upon the whiffletrees after they are formed into the shape above described, although they may be cast in two parts and be secured by proper bolts.

The single-trees are secured upon the double-tree by proper clevises, D, and the draft is applied to proper hooks in the eyes at the ends of the single-trees in the usual manner. The truss, embracing the rod on all sides, prevents the rods coming together at the center, and also does away with the brace heretofore used in whiffletrees of this class.

By this construction we provide a trussed 40 whiffletree which is very strong and capable of doing heavy work, while it is also very light.

We are aware of Patent No. 236,993, and make no claim to the construction shown therein, as we deem our construction as a great improvement over that shown in the above-named patent, inasmuch as we employ no brace, use but one truss for each whiffletree, such truss being constructed to embrace both front and back parts of the rod on all sides 50 thereof, thus rigidly holding the rod in its bent position, and weld the abutting ends of the rod together between the eye and the truss, whereby we produce a stronger, yet lighter, whiffletree than has heretofore been known, at 55 a much less expense.

What we claim as our invention is—

1. A whiffletree made of a single rod of iron bent into the shape shown, provided with eyes upon its ends, and a strut cast thereon to embrace rigidly both back and front parts of the rod on all sides thereof, substantially as described.

2. A whiffletree made of a single rod of iron bent into the form shown, having eyes at each 65 end and a strut at the center, and the back and front parts thereof welded together near the ends of the whiffletree, and between the eyes and the strut, to prevent the parts from slipping upon each other, substantially as de- 70 scribed.

GEORGE H. GASTON.
CHAS. H. GRANT.
